UNITED STATES PATENT OFFICE.

WILLIAM S. OVERLIN, OF PORTLAND, OREGON.

LUMBER-TRUCK.

1,349,292.

Specification of Letters Patent. Patented Aug. 10, 1920.

Application filed November 24, 1919. Serial No. 340,176.

To all whom it may concern:

Be it known that I, WILLIAM S. OVERLIN, a citizen of the United States, residing at Portland, in the county of Multnomah and 5 State of Oregon, have invented new and useful Improvements in Lumber-Trucks, of which the following is a specification.

This invention relates to motor trucks for conveying piles of lumber, or the like, such 10 as the truck disclosed in my Patent No. 1,289,529, issued December 31, 1918, and consists in certain improvements I have made in the power mechanism, that is, the means which transmits the power of the 15 motor either to the driving wheels or to the hoisting mechanism. In my application filed December 14, 1918, Ser. No. 266,667, and patented Dec. 2, 1919, as No. 1,323,719, I have described and claimed one form of 20 such power transmitting mechanism, and the present form is an improvement upon the same.

It is illustrated in the accompanying three 25 sheets of drawings, in which Figure 1 is a perspective of a truck equipped with the mechanism; Fig. 2 is a plan view of the mechanism, and Fig. 3 is an elevation of the same. Figs. 4 and 5 are detail views.

The frame of the truck comprises front 30 and rear arched beam members 10, connected by longitudinal and transverse beams 11, 12, as described in my said patent, and yieldingly supported on the wheels 13 by springs 14, connected by struts 15 to the 35 wheel spindles. 16 represents the load-engaging shoes which, as before, are mounted to slide in the legs of the arched beams and are raised and lowered by means of cables

17. In the present instance, these cables 40 pass over guide sheaves 18 in the arch portion of said beams and are wound around front and rear winding drums 19, carried by a longitudinal shaft 20, on which is mounted a worm wheel 21, driven and held against 45 rotation by a worm 22 on a transverse shaft 23, hereinafter called the hoisting shaft, while the shaft 20 will be referred to as the drum shaft. On the inner end of the shaft 23 is keyed a friction wheel 25, which may 50 be of compressed paper, fiber, or the like.

With the periphery of this wheel are adapted to engage one or the other of two friction disks 24 or 26, carried by the motor shaft 27, according as to whether the load is 55 to be raised or lowered. These disks, which may be made of iron, are independently

movable axially of the motor shaft to engage or be disengaged from said friction wheel 25. A convenient way of providing for this independent movement and that 60 illustrated, is to slidably key one of them, as 26, to the motor shaft 27, and mount the other, 24, rigidly on the end of said shaft, the shaft itself being axially movable in its bearings. To permit this, it is slidably connected to the fly-wheel 28, as shown in Fig. 3.

The friction disk 24 is adapted to also engage the friction wheel 29, which is slidably keyed on the transverse shaft 30, which is 70 square in cross-section, as appears in Fig. 3, and carries the casing 31 of the differential gear through which the power is transmitted to the truck wheels 13 by sun gears 32, 33, shafts 34, 35, sprocket wheels 36, 37, 75 and chains 38 thereon, see Fig. 1, in which, however, only one of the chains is shown.

The object of making the friction wheel 29 slidable on the square shaft 30 is to enable the driver to change the speed of the 80 vehicle at will, and to reverse its direction of travel by sliding the wheel 29 past the center of the disk 24. The means for sliding said wheel consists of a member 40, slidable on a fixed rod 41 and having arms 42, provided at their ends with pins 43, engaging in a groove 44, formed in the hub 45 of said wheel. Member 40 is slid on rod 41 by a link 46, secured at one end to said member and at the other end to a bell-crank lever 47, 90 the other arm of which is connected by a link 48 to a hand lever 49, pivoted at 50 on the frame in convenient proximity to the driver's seat, not shown.

The means for sliding the friction disk 26 95 on the motor shaft 27 consists of a forked lever 51, the arms of which have pins 52 engaging in a groove 53, formed in the hub 54 of said disk, said lever being mounted on a transverse rock-shaft 55, on which is a 100 downwardly projecting arm 56, connected at its lower end to the frame by a spring 57 and having a link 58 pivoted to it between its hub and end.

The other friction disk 24 is put in engagement either with the friction wheel 25 on the hoisting shaft 23, or with the friction wheel 29 on the driving shaft 30, or held disengaged from both of said wheels, by sliding the motor shaft 27, as above stated. 110 The means for sliding said shaft consists of a forked lever 59, the arms of which carry

pins 60, engaging in a groove 61, formed in a collar 62, fast on the shaft, the lever being mounted on another transverse rock-shaft 63, on which is a downwardly projecting arm 64, having a link 65 pivoted to it at its end. The other ends of the links 58 and 65 are slotted, as shown in Fig. 3, to engage, with lost motion, pins 66, 67, respectively, said pins being mounted respectively on the ends of arms 68, 69, carried by a third transverse rock-shaft 70, to the end of which is secured a handle lever 71, by means of which the hoisting friction wheel 25 is caused to be engaged by either 10 the friction disk 24 or the disk 26. With the parts in the position shown in Fig. 3, an upward pull on the lever 71 will cause a pull on the link 65, swing the lever 59 to the right and cause the disk 24 to engage 15 the wheel 25, whereby the load is lifted. On the other hand, a push downward on the handle 71 causes a push on the link 58, thereby swinging the lever 51 to the left and forcing the disk 26 into engagement 20 with the wheel 25.

Additional means are provided to hold the shaft in its adjusted position when it is shifted to engage the disk 24 with the wheel 29 to transmit the power to drive the 25 vehicle, this shifting movement being caused by the driver pressing on a foot pedal 72, the shank of which is pivoted to the end of an arm 73, carried by a short rock-shaft 74. A link 75 connects said arm to an arm 25 76, fast on the rock-shaft 63. The shank of the pedal is formed with ratchet teeth 77, with which engages a pawl 78, pivoted on the frame. To lift the pawl out of the teeth, a link 79 is pivoted to the shank near the 30 point of engagement of the latter with the arm 73 and is connected to another link 80, which in turn is pivoted to the pedal 72, pivoted at 82 to the shank. When the pedal is rocked by the foot of the driver 35 from the full line position to the dotted line position, see Fig. 4, the link 79 lifts the pawl out of engagement, as shown in dotted lines, the pawl being of sufficient width, as shown in Fig. 5, to rest on both the ratchet of the shank and the link 79. An 40 idle roller 84, mounted on the frame member 11, serves to support the pedal shank in its movement.

The operation will now be evident. To 45 raise the load, the driver pulls up on the hand lever 71, putting the disk 24 into engagement with the wheel 25, until the load has been lifted sufficiently, when he releases or pushes down on said lever, the spring 50 83 tending to shift the disk 24 out of engagement as well as also holding the disk 26 away from the wheel 25. The load is maintained in its elevated position by the engagement of the worm and worm wheel, 55 the teeth of which are of such pitch that

the worm cannot be rotated by the worm wheel. To start the vehicle, the driver first slides the wheel 29 near to the axis of the motor shaft 27 by means of the handle 49, and then brings the disk 24 into engagement 70 with the wheel 29 by pressing on the pedal 72. He can lock the pedal against rearward motion when sufficient pressure exists between said disk and wheel, and release it when he wants to stop the vehicle by rocking it on the shank so as to disengage the pawl 78, as described. To lower the load, he pushes down on the hand lever 71, thereby engaging disk 26 with wheel 25.

The mechanism described makes the control and manipulation of vehicles of this kind and of their load very simple, convenient and efficient. Naturally, the details need not be exactly as shown and described; the invention resides in the arrangement and combination of the various elements, as set forth in the following claims.

What I claim is:

1. Driving and hoisting mechanism for 90 motor trucks, comprising the combination with the motor and the load-engaging shoes, of a transmission shaft operatively connected to the truck wheels, a friction wheel adjustable thereon, a hoisting drum shaft, 95 a friction wheel fast thereon, a motor shaft operatively connected to the motor, two axially movable friction disks thereon, one of said disks being adapted to engage the friction wheel on the drum shaft to rotate the latter in one direction, and the other disk being adapted to either engage the same friction wheel to rotate the drum shaft in the other direction, or to engage the friction wheel on the transmission shaft. 100 to drive the wheels, and independent, manually operable means to move said disks into and out of engagement with said wheels.

2. Driving and hoisting mechanism for 110 motor trucks, comprising the combination with the motor shaft, the differential driving shaft and the hoisting shaft, of friction wheels on the driving and hoisting shafts, a pair of friction disks on the motor shaft, means to engage one of said disks with the 115 friction wheel on the hoisting shaft or with the wheel on the driving shaft, and means to engage the other disk with the wheel on the hoisting shaft.

3. Driving and hoisting mechanism for 120 motor trucks, comprising the combination with the wheel driving shaft mounted transversely of the frame and the motor shaft mounted longitudinally of the frame, of a drum shaft mounted parallel to the motor 125 shaft and a hoisting shaft mounted parallel to the driving shaft, worm gearing to connect said drum and hoisting shafts, a friction wheel fast on the end of the hoisting shaft, a friction wheel slidable on the driv- 130

- ing shaft, a friction disk fast on the end of the motor shaft, means to move the motor shaft to bring said disk into engagement with either the friction wheel on the driving shaft or the friction wheel on the hoisting shaft, a friction disk slideable on the motor shaft and means to move it into engagement with the friction wheel on the hoisting shaft.
4. In a motor truck of the class described, the combination of parallel motor and hoisting drum shafts, a wheel driving shaft and a hoisting transmission shaft at right angles to said motor and drum shafts, worm gearing connecting said drum and transmission shafts, friction gearing to connect said motor shaft to said driving shaft and to said transmission shaft, and independent means to control said friction gearing according as to whether the load is to be raised or lowered or the truck is to be driven.
5. In a motor truck of the class described, the combination of a motor shaft, a driving shaft, and a hoisting shaft, a friction wheel on the driving shaft, a friction disk on the motor shaft, and a friction wheel on the hoisting shaft, means to bring said disk into engagement with either of said wheels, means to lock it in engagement with the wheel on the driving shaft, a second friction disk on the motor shaft, and means to bring it into engagement with the wheel on the hoisting shaft.
6. In a truck of the class described, the combination with the motor, the frame uprights, and the load-engaging shoes slideable on the latter, of a drum shaft carrying a worm-wheel and a hoisting drum at each end, cables running from said drums to said shoes whereby the latter are raised or lowered simultaneously, a hoisting shaft, a worm thereon in mesh with said worm-wheel, a friction wheel on the end of said hoisting
- shaft, a motor shaft having a sliding connection with the motor, a friction disk fixed thereon and a second friction disk slideable thereon, means to slide the latter into engagement with said friction wheel, means to move said motor shaft to bring said first friction disk into engagement with said friction wheel, a spring tending to keep both said disks out of engagement with said wheel, a transmission shaft and means to operatively connect it to the driving wheels of the truck, a friction wheel slideable on said transmission shaft, means to slide said wheel to vary the speed of the driving wheels, means to move the motor shaft to engage the said fixed friction disk with the friction wheel on the transmission shaft, and means to lock the motor shaft in adjusted position.
7. A motor truck adapted to straddle and lift the load, comprising arched frame members and load-engaging shoes slideable in the legs thereof, a drum shaft, a pair of drums thereon, cables wound on said drums and running to said shoes, means to drive said shaft in either direction to raise or lower the load including means to sustain the load raised, said driving means comprising a friction wheel and two friction disks either of which can be brought into engagement with said wheel, a differential driving shaft and connections therefrom to the truck wheels, a friction wheel thereon adapted to be engaged by one of said disks, independent means to engage said last mentioned disk with either of said friction wheels, means to lock it in engagement with the wheel on the driving shaft, and means to engage the other disk with the wheel in the driving means for the drum shaft.
- In testimony whereof I have hereunto set my hand.
- WILLIAM S. OVERLIN.
